(57) **CLAIM**

The ornamental design for a caddy, as shown and described.

DESCRIPTION

FIG. 1 is a top perspective view of a caddy in accordance with our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view showing the caddy cover partially removed; and,

FIG. 9 is a perspective view showing the caddy cover completely removed from its base.

The broken lines in the drawings represent portions of the caddy and form no part of the claimed design.

1 Claim, 7 Drawing Sheets
